COMBINED MERCHANTISING AND DISPLAY
STAND FOR PACKAGED PHARMACEUTICAL SUPPLIES OR THE LIKE

Kenneth B. Hawthorne, Princeton, and Frederick A. Maguire, Pompton Plains, N.J., assignors to Johnson & Johnson, a corporation of New Jersey

Filed Feb. 2, 1960, Ser. No. 59,230

Term of patent 14 years

(Cl. D80—9)

FIG. 1

FIG. 3

Fig. 1 is a front perspective view taken from the top and left side of a combined merchandising and display stand for packaged pharmaceutical supplies or the like embodying our new design;

Fig. 2 is a right side elevational view thereof; and

Fig. 3 is a rear perspective view taken from the top and right side thereof.

The dominant features of our design reside in the full-line portions of the drawing.

We claim:

The ornamental design for a combined merchandising and display stand for packaged pharmaceutical supplies or the like, as shown and described.
